AIR LOCK METHOD OF INCREASING TUNNEL CAPACITIES

Application filed February 20, 1930. Serial No. 430,092

This invention relates to tunnels or conduits for transporting liquid, and more particularly to improvements in method and means for increasing the liquid flow capacities of tunnels and other conduits.

Tunnels and other conduits designed for transporting liquids under flow line conditions are usually constructed on moderately flat slopes or grades. It has been observed that when the hydrostatic head on such conduits is increased with the object of increasing the liquid carrying capacity of the conduit by causing the conduit to flow full, such increase in head does not cause a correspondingly proportional increase in flow, because the frictional resistance to flow is increased out of all proportion to the head increase as soon as the conduit is filled and the liquid comes in contact with the roof.

The primary object of the present invention is to provide method and means for increasing the liquid carrying capacity of tunnels and conduits used in transporting liquids. Another and more specific object of the invention is to provide method and means whereby the upper surface of liquid which is being transported through a tunnel under a head sufficient to cause the tunnel to run full, can be kept away from the roof of the tunnel without at the same time materially decreasing the cross-sectional area of the liquid in the tunnel, thereby increasing the hydraulic radius and decreasing the frictional flow resistance of the tunnel.

In order to accomplish these objects the invention contemplates providing and maintaining a series of shallow air pockets between the roof of the conduit and the liquid at a pressure sufficient to hold the liquid away from the roof.

With the above and other objects and features in view, the invention consists in the method and means for increasing the flow capacity of tunnels and conduits for carrying liquid, which is hereinafter described and particularly defined in the claims.

The various features of the invention are illustrated in the accompanying drawings, in which:

Fig. 1 is a longitudinal sectional view,

showing a conduit of square cross-section equipped with means for maintaining a series of shallow air pockets between its roof and the liquid flowing therethrough; and

Fig. 2 is a vertical cross-sectional end view, taken on the line 2—2 of Fig. 1.

In the drawings a tunnel 10 of substantially square cross-section is shown as having its floor and side walls to a height 12 lined with a substantially smooth surface of concrete or the like, and its roof unlined. A conduit of square cross-section has been shown for the purpose of illustrating the invention because application of the present invention to a conduit of square cross-section gives a greater increase in liquid flow capacity than would be the case with a conduit of round or egg-shaped section; though the increase in capacity of a square tunnel is of course less than that which would be effected by application of the invention to a tunnel of flat top basket or rectangular section, having greater width than depth.

Let it be assumed, for example, that the tunnel 10 is 5000 ft. long and is constructed on a slope of 0.5 ft. per 1000 ft. of length. Let it further be assumed that the effective cross-section of the tunnel is 10 ft. in width and 10 ft. in depth, and that the roof of the tunnel is unlined, as illustrated, but is kept above the top of the concrete walls at all points so that it will not be wetted when the tunnel is running full of water to a depth of 10 ft. Assuming further than the roughness coefficient N (of Kutter's formula) is .015, which is a conservative value for ordinary concrete tunnel lining, then applying Cnezy's formula we have the following conditions:

$$A \text{ (area)} = 100 \text{ sq. ft.}$$

$$P \text{ (wetted perimeter)} = 30 \text{ ft.}$$

$$R \left(\frac{A}{P} \right) = 3.33 \text{ ft.}$$

$$V \text{ (velocity)} = 5.0 \text{ ft. per second.}$$

$$Q \text{ (capacity)} = 500 \text{ cu. ft. per second.}$$

If now the head of water at the tunnel entrance is increased so that the tunnel will flow full to the roof, and if it be assumed

that the effective cross-sectional area of the tunnel is not materially increased by so doing, it will be found that the increase in flow capacity of the tunnel will be small and not at all in proportion to the increase in head because of the fact that the hydraulic radius (R) is greatly decreased as soon as the water comes in contact with the roof, with resulting increased friction losses. Thus if it be assumed that the tunnel is completely lined with concrete (including the roof) and that the total effective head from intake to outlet is 10 ft., then (applying Cnezy's formula)

$$\begin{aligned} A &= 100 \text{ sq. ft.} \\ 15 \quad S &= .002. \\ P &= 40 \text{ ft.} \\ R &= 2.5 \text{ ft.} \\ V &= 8.1 \text{ ft. per second.} \\ 20 \quad Q &= 810 \text{ cu. ft. per second.} \end{aligned}$$

If it were possible to hold the water from the roof by means of a continuous film of air without reducing the cross-sectional area of the tunnel, then (applying Cnezy's formula)

$$\begin{aligned} A &= 100 \text{ sq. ft.} \\ S &= .002. \\ P &= 30 \text{ ft.} \\ R &= 3.33 \text{ ft.} \\ V &= 9.9 \text{ ft.} \\ 25 \quad Q &= 990 \text{ cu. ft. per second.} \end{aligned}$$

Obviously it is not possible or practicable to maintain such a thin continuous air film between the roof of the tunnel and the liquid flowing therethrough. According to the present invention, the flow capacity of a tunnel of the foregoing dimensions is increased by forming and maintaining a series of shallow air pockets under the roof of the tunnel throughout its length, so as to hold the water away from the roof. In order to form such air pockets a number of smooth faced concrete roof contractions or air dams 14, of a somewhat flat V shaped cross-section, are built at widely spaced intervals along the roof of the tunnel and extending from side to side thereof (Fig. 2). These roof contractions 14 serve to decrease the effective cross-sectional area of the tunnel in the vertical planes of their apexes and thereby form at such points in the tunnel the equivalents of what might be termed semi-Venturi throats. In a tunnel of the slope and dimensions of the examples previously given, the contractions 14 may, for example, be spaced 1000 ft. apart and at these points the tunnel may, for example, be decreased in height from 10 ft. to 8 1/2 ft.

Air is introduced into the tunnel a short distance below the intake 16 through a pipe 18. The outlet of pipe 18 is located behind an air dam 19 at a higher level than the apex of dam 19 so that air will not escape through the tunnel intake. The air is introduced at a

pressure approximately equal to the static head of liquid in the tunnel measured above the tunnel outlet level 20, less the entrance and velocity heads required to cause flow through the tunnel. This effective head available to overcome friction in the tunnel is, it will be assumed, 10 feet. Since the tunnel is divided by the roof contractions (14) into five sections each 1000 ft. long, then one-fifth of the effective head, or 2 feet, can be utilized in each section for overcoming resistance to flow. The pressure of air in the first shallow pocket or lock 22 thus formed is of course uniform over the entire surface area of water beneath such pocket, and is sufficient to hold the water away from the roof. The velocity imparted to the water by the velocity head at the entrance of the tunnel will not only be maintained but increased as the liquid flows downwardly through the section of the tunnel under airpocket 22, by the surface slope which the water will automatically assume in flowing from the entrance of the tunnel to the Venturi throat 23 formed by the first main air dam or roof contraction 14. Since Q (i. e. the volume flow) is the same at all points in the tunnel and since the cross-sectional area of the tunnel is greater at the upper end of each 1000 feet section (100 sq. ft.) than at the lower end (85 sq. ft.), the slope of the upper surface of the liquid gradually increases to maintain the increase in velocity flow, the total surface drop in such 1000 ft. section being 2 ft. When the air pressure in the first pocket 22 exceeds the 10 ft. of effective water head, the water surface will be slightly depressed at the first roof contraction 14 by air flowing with the water from the first section or air pocket into a second air pocket 24 in the second 1000 ft. section of the tunnel. The air pressure in the second pocket 24 will be maintained at two ft. less head than that in the first pocket. Assuming a continuous supply of air through the pipe 18, the air pressures in the successive air pockets will be automatically regulated and will decrease by decrements of 2 ft. of head from a pressure of 10 ft. in the first pocket to zero at the tunnel outlet. Since the effective flow areas, pressure difference and slope are the same beneath all pockets a uniform flow of liquid will be maintained throughout the whole tunnel.

Under the conditions assumed in the above example, the calculated flow capacity of the tunnel with the air pockets dimensioned as above described is 910 cu. ft. per second. This flow capacity is 410 cu. ft. per second greater than the capacity of the tunnel operating on flow line grade, or an increase of 85%, and is 100 cu. ft. per second or 12 1/2% greater than the capacity of a completely lined tunnel operating under the same head. While there is of course a slight resistance to flow offered at points where the water surface

- comes in contact with the roof contractions 14, the total length of such points of contact is very small, particularly when air is fed to the tunnel at a reasonably rapid rate. If it be 5 assumed that the total length for such points of contact is 100 ft. the consequent loss of head is calculated to be only about 0.25 ft. Such additional head loss would decrease the calculated capacity indicated below the figure 10 given, but conservative calculations indicate that by means of five roof contractions 14 of the dimensions illustrated and the air pockets maintained thereby, the capacity of the 5000 ft. tunnel of the example is increased 15 75% over flow line conditions and at least 10% over the capacity of a completely lined tunnel operating under the same head.

In case the liquid head on the tunnel should be less than the maximum of 10 ft. 20 effective head assumed in the foregoing example, the pressure at which air is introduced into the tunnel should be reduced proportionately to a value approximately equal to the effective head. In every case the reduction of air pressure in the successive air 25 pockets will be automatic, just as when the maximum head is operative, and a reduced flow will be maintained by the flatter surface slope in the tunnel. As the effective head 30 is reduced the drop of water just below the roof contractions will be less, but the depth directly under the contractions will remain constant until the effective head is reduced to less than that required to maintain free 35 surface flow, when of course the surface slope will be parallel to the slope of the tunnel.

The principles of the present invention may be applied to existing pressure tunnels or to portions of such tunnels, with resulting 40 increase in flow capacity of the tunnels when operating under the same effective head. The quantity of air that is required to maintain the air pockets throughout the length of the tunnel or conduit depends upon the capacity 45 of the water or other liquid carried by the conduit for air absorption, and on the amount of air leakage. Most liquid tunnels through rock can be readily and effectively sealed against air leakage by caulking, 50 plastering, or grouting the cracks and seams in the rock. Normally the volume of air absorbed by the water or other liquid is not a serious item.

For regulating the rate of admission of air 55 to the tunnel, a valve 26 is mounted in the air supply line 18 and arranged for automatic operation by means of a float 28 located in the forebay 30.

Wherever additional entrance head is available, and where the roof of the tunnel is of 60 such nature that it can be made practically air tight, flow line tunnel capacity can be readily increased by the present air lock system at a cost well below the cost of completely lining the roof for operation as a

pressure tunnel, with the resulting additional advantage of higher flow capacity over that of a fully lined pressure tunnel without such air locks.

The invention having been thus described, 70 what is claimed as new is:

1. The method of increasing the liquid flow capacity of a conduit of moderate slope which comprises, establishing a hydrostatic head on the conduit sufficient to cause it to run full of liquid, and maintaining a series 75 of shallow air pockets between the roof of the conduit and the surface of the liquid flowing therethrough.

2. The method of increasing the liquid flow capacity of a conduit of moderate grade which comprises, establishing a hydrostatic head on the conduit sufficient to cause it to run full of liquid, and maintaining a series 80 of shallow air pockets between the roof of the conduit and the surface of the liquid, the air pressure in each of said pockets being approximately equal to the static head on the liquid flowing beneath said pocket.

3. The method of increasing the liquid flow capacity of a conduit running full of liquid which comprises, fractionally contracting the cross-sectional area of the body 90 of liquid flowing through the conduit at spaced intervals, and maintaining a shallow air pocket between the roof of the conduit and the flowing liquid on the upstream side of each of said contractions.

4. In a conduit for transporting liquid, a series of smooth faced roof contractions located at spaced intervals throughout the length of the conduit and extending from side to side thereof, and means operable in conjunction with said roof contractions to maintain a shallow air pocket on the upstream side of each of said roof contractions 100 between the conduit roof and the surface of liquid flowing therethrough.

5. In a conduit for transporting liquid having a forebay at its inlet end, a plurality of roof contractions located at spaced intervals longitudinally of the conduit whereby the effective cross-sectional area of the tunnel is fractionally reduced, and means for automatically maintaining shallow air pockets under the roof of the tunnel in front of each of said roof contractions during periods in which the head of liquid in said forebay is sufficient to cause the conduit to run full. 110

In testimony whereof I affix my signature. 120
